UNITED STATES PATENT OFFICE.

GEORGE R. WILLETT, OF PITTSBURGH, PENNSYLVANIA.

FUSE.

1,028,647.

Specification of Letters Patent.

Patented June 4, 1912.

Application filed October 27, 1911. Serial No. 657,095.

To all whom it may concern:

Be it known that I, GEORGE R. WILLETT, a citizen of the United States of America, residing at Pittsburgh, in the county of Allegheny and State of Pennsylvania, have invented certain new and useful Improvements in Fuses, of which the following is a specification, reference being had therein to the accompanying drawing.

10 This invention relates to fuses, and my invention aims to provide:—first, a cartridge fuse having provision for holding a soft metal fuse centrally of the cartridge. Second, a cartridge fuse with detachable caps 15 for permitting of easy access being had to the interior of the cartridge for replacing a fuse. Third, a cartridge fuse that is simple in construction, durable and safe to use.

The invention further aims to accomplish 20 the above results by a combination of related elements that will be hereinafter specifically described and then claimed, and reference will now be had to the drawing, wherein there are illustrated the preferred 25 embodiments of the invention, but it is to be understood that the structural elements thereof are susceptible to such changes as fall within the scope of the appended claims.

In the drawing like numerals denote 30 corresponding parts throughout the several views, in which:—

Figure 1 is a plan of the fuse partly broken away and partly in section, Fig. 2 is a longitudinal sectional view of the fuse, 35 Fig. 3 is a plan of the cartridge, Fig. 4 is a plan of a detached cap, Fig. 5 is an end view of the same, Figs. 6, 7 and 8 are side elevations of portions of fuses, showing various types of nuts associated with the detachable 40 caps of the fuses, Fig. 9 is a longitudinal sectional view of a portion of a modified form of fuse, Fig. 10 is a perspective view of a portion of the cartridge of said fuse, and Fig. 11 is a perspective view of a detached cap.

The reference numeral 1 denotes a cylindrical cartridge shell made of a non-conducting material, as fiber. The shell 1, at the ends thereof, is provided with open slots 50 2 and openings 3 diametrically disposed relatively to the closed ends of the slots 2.

The reference numeral 4 denotes transverse sleeves arranged in the ends of the cartridge shell and alining with the openings 3 and the closed ends of the slots 2. These sleeves receive screws 5 having nuts 6.

The reference numeral 7 denotes metallic caps fitted upon the ends of the cartridge shell 1. The caps have the walls thereof provided with diametrically opposed open 60 slots 8 and 9, the latter being of a greater length than the former. The end walls of the caps 7 are provided with openings 10 that are normally closed by a disk of paper 11, preferably thin asbestos paper. The 65 caps are fitted upon the ends of the cartridge shell with the slots 8 registering with the openings 3 to provide clearance for the screws 5 and the slots 9 registering with the slots 2 of the cartridge shell to provide 70 clearance for the screws, also for a purpose that will presently appear.

The reference numeral 12 denotes a soft metal fuse made of soft lead or other fusible material. This fuse is arranged longitudinally of the cartridge shell and the ends are carried around the sleeves 4, upwardly through the slots 2 and 9 and under the nuts 6, said nuts being tightened upon the screws 5 to bind the ends of the fuse between the 80 caps and said nuts, besides locking the caps upon the ends of the cartridge fuse.

Fig. 6 shows a knurled nut 13 in lieu of the nut 6.

Fig. 7 shows a winged thumb nut 14 in 85 lieu of the nuts 6 and 13.

Fig. 8 shows one of the caps 7 as provided with a blade 15, whereby it can be used in a knife switch.

In Figs. 9 to 11 inclusive, there is illustrated a modification of the invention, wherein the ends of the cartridge shell 16 are provided with longitudinal grooves 17 and diametrically opposed pins 18. The caps 19 fitted upon the ends of the cartridge 95 shell 16 are provided with oppositely disposed L-shaped slots 20 to receive the pins 18, whereby the caps 19 can be locked upon the ends of the cartridge shell. A fuse 21 is located centrally of the cartridge shell 16, 100 and the ends of the fuse are carried upwardly into the grooves 17 and retained therein by the caps 19.

To recapitulate, the sleeves 4 prevent crystallization of the screws 5 when the fuse 105 12 is burned out, the disks of paper 11 preventing an unnecessary escape of fumes when the fuse is burned out, yet permitting an excessive pressure of fumes to escape at the openings 10. Considerable importance is attached to the fact that the ends of the fuse are carried to the outer sides 110

of the caps 7 and anchored thereto by means that serves to hold the caps in engagement with the cartridge shell.

I reserve the right to line the cartridge 5 fuse with asbestos or fill the same with a non-fusible material.

What I claim is:—

1. A cartridge fuse comprising a non-fusible cartridge shell having the ends there- 10 of slotted, transverse sleeves located within the slotted ends of said shell, screws ex- tending through said sleeves, and a soft metal fuse located longitudinally of said shell and having the ends thereof extending 15 through the slots of said shell and around said screws and held in engagement therewith.

2. A cartridge fuse comprising a non-fusible shell having the ends thereof slotted, 20 caps detachably mounted upon the ends of said shell and having slots registering with the slots of said shell, screws arranged transversely of the ends of said shell and extending through the slots of said shell 25 and the slots of said caps, a fuse arranged longitudinally of said shell and having the ends thereof extending through said slots and around said screws, and means carried by said screws for anchoring the ends of 30 said fuse upon said caps.

3. A cartridge fuse comprising a non-fusible shell having the ends thereof pro- 35 vided with slots, caps detachably mounted upon the ends of said shell and having slots communicating with the slots of said shell, transverse screws arranged in the ends of said shell and extending through the slots of said shell and said caps, a fuse arranged

within said shell and having the ends there- 40 of extending through said slots and engag- ing said screws, nuts screwed upon said screws for retaining the ends of said fuse in engagement with the outer sides of said caps, and means surrounding said screws within said shell for bracing the walls of 45 said shell during the screwing action of said nuts.

4. A cartridge fuse comprising a shell having the ends thereof slotted, screws ar- 50 ranged transversely of said shell and ex- tending through the slots of said shell, a fuse arranged longitudinally within said shell and having the ends thereof extending through the slots of said shell and in en- gagement with the ends of said screws, nuts 55 screwed upon the ends of said screws for retaining the ends of said fuse in engage- ment therewith, and means surrounding said screws within said shell for bracing the walls of 60 said shell during the screwing action of said nuts.

5. A cartridge fuse comprising a shell having the ends thereof slotted, screws ar- 65 ranged transversely of said shell and ex- tending through the slots of said shell, and a fuse located longitudinally of said shell and having the ends thereof extending through the slots of said shell and held in engagement with one end of each screw.

In testimony whereof I affix my signature 70 in the presence of two witnesses.

GEORGE R. WILLETT.
